J. A. A. FONTAINE, OF NEW YORK, N. Y.

Letters Patent No. 61,824, dated February 5, 1867.

IMPROVED AERIAL RAILROAD.

The Schedule referred to in these Letters Patent and making part of the same.

TO ALL WHOM IT MAY CONCERN:

Be it known that I, J. A. A. FONTAINE, of the city, county, and State of New York, have invented a new and improved Aerial Railroad; and I do hereby declare that the following is a full, clear, and exact description thereof, which will enable others skilled in the art to make and use the same, reference being had to the accompanying drawings, forming part of this specification, in which—

Figure 1 represents a perspective view of my improved aerial car and railway.

Figure 2 is a vertical longitudinal section of a portion of the car.

Figure 3 is a vertical cross-section of the elevated railway taken on a plane indicated by the line $z z$, fig. 1.

Figure 4 is a detail view to be hereinafter referred to.

Similar letters of reference indicate like parts.

This invention relates to a novel application of steam power to a railroad car which is propelled on an elevated track, the weight of said car being diminished or rendered negative by the attachment of a balloon to the said steam car. Sails may also be arranged on the car. Thus this apparatus will, for traversing level roads, be propelled either by steam power or by the wind, the balloon being so shaped as to offer the least possible surface and resistance to the atmospheric air in front. For ascending the balloon will be sufficient to propel the car, while steam and atmospheric power have to be used for descending, for which purpose, also, a weight may be attached to the front or lower end of the car. Hand or spring power may be substituted for the steam power on small cars. The wheels of my car are provided with deep grooves around their peripheries. The wheels travel between double rails, that is to say, one rail is below and one above the wheels. If the weight of the balloon is positive, then the wheels travel on the lower rail; if negative, the wheels revolve on the upper rail, as in the latter case the balloon has the tendency to raise the car. This railroad is to be applied for crossing rivers or swamps, for ascending hills, and even for travelling over the level ground.

I am aware that elevated railways have been constructed or invented already for steam cars; I am also aware that balloons are used for raising cars up hill; but never yet have balloons been combined with steam or lever power, and with sails, for the purposes herein set forth and as hereinafter more fully described.

The balloon car A is made of silk, or other suitable material, supported on the inside by a suitable light framework, and covered on the outside by a network of sufficient strength. The whole surface is covered with a varnish, or other composition, whereby the hydrogen gas is prevented from escaping through the enclosure of the balloon. The shape of the car may be as shown in fig. 1, that is, cylindrical, with conical ends, B B, or it may have any other shape which may be found to be most practicable and whereby the car will offer the least resistance to the air. Within the body of the balloon car, or elevated above it, or otherwise connected with it, is a structure, C, which contains the steam (or other) engine, the cabins, store-rooms, &c. One or more of such structures may be arranged on each car, according to the size and design of the car A. For the purpose of keeping and securing the substantial structure well and secure in the flexible balloon, I propose to arrange a light framework around the structure, and support it by ropes D which are held in the metal rings E, as shown in fig. 2. The engine, which may be operated by steam, water, condensed air, lever, or spring power, and which is shown in fig. 2, revolves a horizontal shaft, F, on either end of which a wheel, G, is secured. This wheel, as well as all the other wheels, H, which are simply attached to the side of the car, is deeply grooved, as shown in fig. 3, so as to be prevented from running out of the track. All the wheels on each side of the car are connected with each other by a bar, I. The bar I is provided with universal joints, which allow of the expansion and contraction of the bar I, as well as of any bending of the same. A joint, as I propose to make it, is shown in fig. 4, where two ends, $z z$ and $z z'$, of the bar I are connected by a rod, i; said rod sliding in the end $z z'$ of one bar, and the other end being provided with a ball which can turn and is held in the end of the other bar I. The track consists of two wire ropes or flexible rods, K, on either side of the way. For certain purposes the rails may be made of solid iron or wood. The rails are supported by posts, L, in the manner shown in fig. 3. The posts are provided with two elbow arms, l and l'; to the respective upper or lower end of each a rail is secured. Thus the rails are continued through the supporting posts L. A sail, M, is secured to a mast, N, as shown in fig. 1. The posts L, which support the rails, are of course well secured to the ground.

What I claim as new, and desire to secure by Letters Patent, is—

1. The combination of the balloon car A with the structure C, driving-shaft F, sail M, when arranged and applied in connection with an elevated track K, substantially as and for the purpose herein shown and described.
2. I claim the posts L, provided with arm l and l', for the purpose of continuing the track K, substantially as herein shown and described.

J. A. A. FONTAINE.
